UNITED STATES PATENT OFFICE.

FRANK H. HOBERG AND COMADORE C. THOMAS, JR., OF GREEN BAY, WISCONSIN.

COUCH-ROLL.

1,228,114.

Specification of Letters Patent. Patented May 29, 1917.

Application filed August 23, 1915. Serial No. 46,981.

To all whom it may concern:

Be it known that we, FRANK H. HOBERG and COMADORE C. THOMAS, JR., citizens of the United States, residing at Green Bay, 5 county of Brown, and State of Wisconsin, have invented new and useful Improvements in Couch-Rolls, of which the following is a specification.

Our invention relates to improvements in 10 couch rolls.

The ordinary suction couch roll comprises a hollow cylinder covered with fine wire, 15 felt or equivalent foraminous material through which water may be drawn by suction, air and water being continuously withdrawn from the interior of the cylinder by a suitable pump. In these structures the outer cylinder covering or jacket performs 20 no function except to support the pulp carrying belt or apron and allow the passage of water through it. But we have discovered that much better results can be obtained by employing an elastic covering of absorbent material which will be 25 compressed by the pressure of the pulp carrying belt or apron and will quickly expand and resume its original form when such pressure is relieved in a manner to maintain contact with the belt or apron in the 30 angle between the belt or apron and the cylinder, where the apron leaves the cylinder tangentially. We have discovered that by using such a covering, the expansion of the material will create suction sufficient to absorb 35 considerable quantities of water from the pulp carrying apron and that this water may be drawn into the cylinder before the portion of the jacket which absorbed it is again brought in contact with the apron by 40 the continued revolving movement of the cylinder. Also that the presence of the relatively large quantity of water absorbed by such a jacket tends to exclude air and therefore increases the effective vacuum within 45 the cylinder, it being well known that the air has heretofore entered the cylinder on the side where the apron is out of contact therewith much more freely than on the side which is covered by the apron.

50 We have also discovered that an elastic covering jacket of absorbent material may be employed upon a solid roller and utilized to extract water from the apron and pulp carried thereby, owing to the fact that the jacket creates its own suction to absorb water from the apron in the zone of diver-

gence, whereas on the other side where the apron comes into initial contact with the jacket, the compression of the jacket by the apron expels the water. It will of course 60 be understood that the pulp is fed to the apron along an intermediate zone where the jacket is under full compression as exerted by the apron, the water previously absorbed by that portion of the jacket having 65 already been expelled by the apron pressure and the reexpansion of the jacket taking place shortly after the deposit of the pulp upon the apron. To secure the desired results it is of course necessary that a material 70 be employed which will not mat, but will permanently retain its elastic and absorbent qualities.

The object of our invention is therefore to increase the efficiency of suction couch rolls 75 by providing such rolls, whether hollow or solid, with an elastic jacket of absorbent material capable of permanently retaining its elastic and absorbent qualities.

In the drawings—

Figure 1 is an end view, partially in transverse section, showing a suction couch roll embodying our invention.

Fig. 2 is a perspective view of one end portion of a couch roll of the solid cylinder 85 type embodying our invention.

Fig. 3 is a view, showing a fragment of the jacket developed.

Like parts are identified by the same reference characters throughout the several 90 views.

The suction couch roll illustrated in Fig. 1 embodies a central tubular shaft 1 through which the suction is applied, and a cylinder 2 supported from the shaft by radially disposed tubular spokes 3, the periphery of the cylinder 2 being covered with a built up structure of wire and supporting members of progressively diminishing cross section, such as are shown and described in our former application, filed April 19, 1912, Serial No. 691933, and allowed April 23, 1915, which has resulted in Patent No. 1,159,381, dated November 9th, 1915.

In the structure shown and described in 105 our former application, however, the outer covering of the cylinder comprises a jacket of felt which is inelastic and incapable in itself of continuously absorbing moisture from the pulp apron 4, whereas the jacket 5 illustrated in Fig. 1 is a thick knitted jacket composed of thick strands of loosely twisted

woolen yarn. We have discovered that a woven or knitted woolen jacket possesses the elastic qualities above mentioned and that it is capable of continuous expansion 5 and contraction for an indefinite period of time. Also that when expanding in the angle where the apron leaves the cylinder tangentially, this woolen jacket will rapidly absorb water from the apron and the pulp 10 carried thereby independently of the suction exerted from the interior of the cylinder due to the maintenance of a partial vacuum therein. The water thus absorbed by the jacket also tends to exclude air from 15 the cylinder on that side which is not covered by the apron, although of course this exclusion will become less and less effective as the water is withdrawn into the cylinder. On the side where the apron initially contacts with the cylinder, the compression of 20 the jacket by the apron greatly facilitates the withdrawal of the residue of the water in the jacket, so that by the time any given portion of the jacket reaches the point 25 where fresh pulp is delivered upon the apron, the jacket will have been compressed and dried to a point where it will possess substantially a maximum absorbing capacity and will therefore, as above stated, withdraw 30 large quantities of water from the apron 4 and the pulp 6 as soon as the pressure of the apron begins to reduce.

In the construction as illustrated in Fig. 1, the moisture absorbing zone above described 35 and in which the jacket absorbs water by its own suction, is indicated between the points *a*—*b*. The jacket compressing zone is indicated between the points *c*—*d*, the direction in which the apron travels being indi-

cated by the arrows and the pulp-delivering 40 wheel being indicated at *e*.

In the structure shown in Fig. 2, the cylinder 7 is a solid cylinder. The jacket 8 is similar to the jacket 5, shown in Fig. 1, and is composed of woven or knitted material 45 having the elastic qualities of a woolen jacket, the strands preferably being large and coarse or loosely twisted, so as to secure the most effective moisture absorbing action. The operation of this jacket 8 is the 50 same as above described with reference to Fig. 1, except that the water is not expelled by being drawn into the interior of the cylinder and in fact is not expelled at all along that portion of the cylinder not covered by 55 the apron, but on the contrary in the cylinder shown in Fig. 2, the water is expelled very rapidly in the zone where the apron comes into initial contact with the jacket and compresses the jacket between it and the 60 cylinder surface.

We claim—

1. A suction roll covering, consisting of a knit sleeve, said sleeve adapted to be pulled over a suction roll and cover the periphery 65 thereof, substantially as set forth.
2. A suction roll covering, consisting of a coarsely knit woolen sleeve, said sleeve adapted to be pulled over a suction roll and cover the periphery thereof, substantially 70 as described.

In testimony whereof we affix our signatures in the presence of two witnesses.

FRANK H. HOBERG.

COMADORE C. THOMAS, JR.
